UNITED STATES PATENT OFFICE.

GEORGE SHANK, OF SEYMORE, INDIANA.

DESIGN FOR A STEAM CLOTHES-WASHER.

SPECIFICATION forming part of Design No. 34,629, dated June 4, 1901.

Application filed April 22, 1901. Serial No. 57,025. Term of patent 14 years.

To all whom it may concern:

Be it known that I, GEORGE SHANK, a citizen of the United States, residing at Seymour, in the county of Jackson, State of Indiana, have invented and produced a certain new and original Design for a Steam Clothes-Washer, of which the following is a specification, reference being had therein to the accompanying drawings.

- Figure 1 is a perspective of my design for a steam clothes-washer. Fig. 2 is a vertical longitudinal section thereof, and Fig. 3 is a vertical cross-section.

As shown in the drawings, the leading or material feature of my design consists of the centrally-depressed base, having at opposite sides between its ends vertical standards, with parallel horizontal arms projecting in opposite directions from said standards. The base A, as shown, is elliptical in outline and depressed toward the center A', where perforations A² are provided. In the same plane as the vertical wall A³ of the base A the opposite standards B rise and are provided with

cross-arms B', extending therefrom at the top 25 thereof and midway of their height. Both the standards and arms are shown as triangular in cross-section and provided with perforations B² upon their inclined faces. At the opposite ends of the base A standards C 30 are provided, having a curved inner face C' and perforations C² upon said face. The standards B and C are connected at their upper ends by a band D, which extends parallel with the upper cross-arms B' upon the standards B.

Having described my invention, what I claim as new, and desire to secure by Letters Patent, is—

The design for a steam clothes-washer as 40 herein shown and described.

In testimony whereof I affix my signature in presence of two witnesses.

GEORGE SHANK.
